UNITED STATES PATENT OFFICE.

PETER HALLEN, OF BROOKINGS, SOUTH DAKOTA.

COMBINED COAT AND HAT RACK.

No. 844,864.

Specification of Letters Patent.

Patented Feb. 19, 1907.

Application filed November 5, 1906. Serial No. 342,047.

To all whom it may concern:

Be it known that I, PETER HALLEN, a citizen of the United States of America, residing at Brookings, in the county of Brookings and 5 State of South Dakota, have invented certain new and useful Improvements in a Combined Coat and Hat Rack, of which the following is a specification.

This invention relates to furniture, and 10 particularly to a stand designed for use as a combined hat and coat rack.

An object of this invention is to provide a novel device having a shelf-like structure on which hats may be deposited; and it is 15 further provided with a series of hooks to support garments, the said stand comprising duplicate parts on two sides suitably separated by a screen, so that the garments on one side may not contact with those on the 20 other side.

A further object of this invention is to provide a stand of this character with a holder which may clamp and retain umbrellas, the 25 said holders being preferably on the ends of the stand.

A further object of this invention is to provide a hat, a coat stand or rack of ornamental design and made, preferably, of metal, the parts of which are of graceful contour and 30 of such rigid construction as to support unusual weights for a stand of this character.

With the foregoing and other objects in view the invention consists in the details of construction and in the arrangement and 35 combination of parts to be hereinafter more fully set forth and claimed.

In describing the invention in detail reference will be had to the accompanying drawings, forming part of this specification, 40 wherein like characters denote corresponding parts in the several views, in which—

Figure 1 is a view showing a side elevation of the stand embodying the invention. Fig. 2 is a vertical sectional view on the line 2 2 of 45 Fig. 1. Fig. 3 is a plan view of the umbrella-clamp.

In these drawings, A indicates a series of supports, each support being made in two duplicate sections, each of said sections comprising 50 a vertically-disposed member of metal B, with its lower portion outwardly bent, as at C. The duplicate sections B are opposed, and the central portions thereof lie parallel one with the other. The rods D D, each comprising two half-round sections, are secured to the members B, and a wire screen

E is clamped between the sections of the rods and forms a partition between the two sections of the stand to prevent the garments of one side from contacting with the garments on the other side. The upper rod D is provided with a series of hooks F, which hooks are approximately C-shaped and are designed for the purpose of supporting coats and wraps and the like, the inner ends of said 65 hooks being bolted to the rod.

The bars B C are provided with a series of braces G, H, and I, bolted to each other and to the said bars B C, as fully shown in Fig. 2, the said braces being suitably curved to produce an ornamental effect. A brace J is interposed between the brace G and the member B and is secured to the said member and to the lower rod D by means of bolts which extend through the braces and through the 75 rod D. The legs formed by the members C and the braces G are further strengthened by the use of braces K, each of which extends from the bottom of the member C inwardly to a point of juncture with the opposite brace 80 and is then curved to again contact with the member C, where it is secured by the bolt L. The contiguous sections of the two braces K are joined together by a bolt M. The duplicate sections of each support are secured together at the top by a binding-strip N, suitably bolted to the sections of the support, and this binding-strip may be of any construction, though it is here shown as having curved ends and a looped central portion to 85 give an artistic finish to the structure.

Extending longitudinally of the supports and secured thereto at the upper portions thereof are the coat-racks O, consisting of rods having hooks attached thereto, and at 95 the time the rods are attached to the supports it is my purpose to interpose between the rods and the supports the edges of a wire screen, which forms the shelf O for supporting hats and headgear. It is preferable to have this shelf O of screen or perforated metal, as it prevents the accumulation of dust thereon and renders the said shelf sanitary.

The umbrella-supporting device P comprises a strip of wire having a series of loops 105 therein, the edge of one loop overlapping or touching the next succeeding loop in order that the umbrella may be braced between the two loops in such a way as to afford a 110 spring action on the umbrella for retaining it in place. The ends of the wire forming the

umbrella-support are secured to the end supporting members through the medium of bolts, and the said umbrella-holding device is supported intermediate its length through 5 the medium of a hanger which is attached to said umbrella-retaining device and extends upward and is secured to the support. The exact construction of this device is shown in Fig. 3.

Having fully described my invention, what I claim as new, and desire to secure by Letters Patent, is —

1. In a garment-holder, a stand consisting of supports each comprising two sections opposed one to the other longitudinally, a 15 screen held between the opposed faces of the sections, and a shelf supported by the sec-

tions and extending to either side of the screen.

2. In a garment-holder, a stand consisting 20 of suitable supports, each support comprising two sections rods clamped between the sections, a wire screen extending from one rod to the other and secured thereto, hooks on the rods, hooks supported near the top of the stand, and a shelf attached to the supports and extending to either side of the screen.

In testimony whereof I affix my signature, in the presence of two witnesses, this 26th day of October, 1906.

PETER HALLEN.
